(57) **CLAIM**

We claim the ornamental design for a turbine blade for a turbine blade attachment assembly, as shown and described.

DESCRIPTION

FIG. 1 is a perspective view of a turbine blade for a turbine blade attachment assembly embodying the invention.

FIG. 2 is a first end view thereof;

FIG. 3 is a second end view thereof;

FIG. 4 is a first side view thereof;

FIG. 5 is a second side view thereof;

FIG. 6 is a top plan view thereof; and,

FIG. 7 is a bottom plan view thereof.

The elements shown in broken lines are included for the purpose of illustrating environment and form no part of the claimed design. Any omitted views form no part of the claimed design.
